UNITED STATES PATENT OFFICE

153,872

DESIGN FOR A TAXICAB CRUISING LAMP

Robert W. Garrett, Washington, D. C.

Application September 22, 1948, Serial No. 148,708

Term of patent 7 years

(Cl. D48—32)

To all whom it may concern:

Be it known that I, Robert W. Garrett, a citizen of the United States, residing at Washington, in the District of Columbia, have invented a new, original, and ornamental Design for a Taxicab Cruising Lamp, of which the following is a specification, reference being had to the accompanying drawing, forming part thereof.

Figure 1 is a perspective view of a taxicab cruising lamp, showing my new design;

Figure 2 is a front elevational view thereof;

Figure 3 is a top plan view;

Figure 4 is a side elevational view, and

Figure 5 is a rear elevational view of the same.

I claim:

The ornamental design for a taxicab cruising lamp, as shown.

ROBERT W. GARRETT.
